UNITED STATES PATENT OFFICE.

JOHN H. SUTER, OF LOS ANGELES, CALIFORNIA.

METHOD OF AND MEANS FOR FUEL INJECTION FOR INTERNAL-COMBUSTION MOTORS.

Application filed June 7, 1920. Serial No. 387,094.

To all whom it may concern:

Be it known that I, JOHN H. SUTER, a citizen of the Republic of Switzerland, residing at Los Angeles, in the county of Los Angeles and State of California, have invented new and useful Improvements in a Method of and Means for Fuel Injection for Internal-Combustion Motors, of which the following is a specification.

10 This invention relates to internal combustion engines of the type in which hydrocarbon oil or other vaporizable fuel is introduced into the cylinder and ignited by the reason of the temperature attained by the 15 highly compressed air contained therein.

The present invention relates to a method and means for forcing the charge of fuel in to the cylinder against the highly compressed air therein. Certain methods and 20 means have been devised employing an auxiliary chamber in communication with the cylinder, into which chamber the oil is introduced and a portion of the charge in the chamber is caused to ignite by reason of 25 the heat of the compressed air. A foul or primary explosion then occurs which ejects the remainder of the charge into the cylinder. Devices of this character have met with two primary difficulties. It has been 30 the common practice to introduce the fuel charge substantially coincident with the instant of greatest compression of the air in the cylinder. This requires careful timing of the events. Another trouble encountered 35 has been that of cracking of the hydrocarbon due to the heat retained by the walls of the chamber, and premature explosions also occur. In some constructions, the structure of the chamber and its associated parts has 40 been purposely designed to distill some of the hydrocarbon. A residue results from the cracking and distillation, which clogs the passages of the chamber and soon renders the device inoperative.

45 The objects of my invention are to provide a means and method of introducing the fuel charge into the cylinder by means of a foul explosion in an auxiliary chamber, which, first, will not produce carbonaceous deposits; second, will not require exact timing for the introduction of the charge into the chamber; and third, will direct the fuel charge into the clearance space of the engine and not upon the piston.

I accomplish these objects by means of the 55 engine illustrated in the accompanying drawing, in which:

Fig. 1 is a vertical section of the upper end of an engine cylinder equipped for carrying out my invention; Fig. 2 is a fragmentary section as seen on the line 2-2 of Fig. 1; and Fig. 3 is an enlarged section as seen on the line 3-3 of Fig. 1.

Referring more particularly to the drawing, 4 indicates the cylinder of an internal 65 combustion engine having a piston 5 disposed therein. Mounted in the head 6 of said cylinder is the fuel injection device employed in carrying out my invention.

At the internal wall of the cylinder and 70 extending through the head is an opening for the fuel injection device. It comprises an injection nozzle 7 held in position between an annular shoulder 8 and a follower 9. A plug 10 is held in position between the 75 nozzle and the follower. Mounted in the plug is a fuel nozzle 11, which extends into a chamber in the injection nozzle.

The injection nozzle 7 is formed with an internal chamber 12 extending longitudinally therein, and communicating at its inner or discharge end with an outlet passage 13, preferably flattened and diverging toward ducts 14 for spraying the charge into the clearance space of the cylinder transverse 85 of the piston travel. The upper end of chamber 12 is counter-bored to receive the plug 10. The injection nozzle 7 is recessed externally adjacent the contracted end, as indicated by 15, to form passages for the circulation of water from the water jacket 16 90 in the cylinder head.

The plug 10 has an enlarged lower end snugly fitting in the counter-bore of the injection nozzle. The upper end is of the reduced diameter and extends through an opening in the follower 9. The latter has an extension engaging the shoulder of the plug, forming a gland as well as holding the plug in position. The nozzle 11 ends at the 100 counterbore in the plug 10, in which is disposed a cage 17 containing a check valve. Connected to the cage by any suitable means is a fuel supply pipe 18 for supplying liquid fuel under pressure to the nozzle.

It will be noted that the injection nozzle is completely surrounded by a water jacket, thereby maintaining the auxiliary chamber

cool and at a uniform temperature. This is an important feature of my invention, as will be later noted.

The operation of the invention is as follows:

During the compression stroke of the engine, air (which has been drawn into the cylinder during the preceding stroke in a four cycle engine, or forced into the cylinder 10 at the beginning of the compression stroke in a two cycle engine) is compressed in cylinder 4, and a part of such compressed air passes into the chamber 12 through the ducts 14. At or before the end of the compression stroke, liquid fuel is forced (by suitable means operated by the engine) through pipe 18 and nozzle 11 into the chamber 12. Some of the fuel charge is mixed 15 with the air forming an explosive charge 20 filling a portion of the chamber 12. When the air in the chamber has reached a temperature (due to compression), which is above the ignition temperature for the fuel to be used, combustion of the explosive charge 25 immediately takes place, resulting in a sudden increase of pressure of the gases in the chamber 12, which, forces the remainder of the fuel charge outwardly through the ducts 14 into the cylinder of the engine. The fuel 30 injected into the cylinder ignites and the piston 5 is forced outwardly.

The walls of the injection nozzle and its chamber are maintained at a uniform temperature by the cooling water of the jacket. 35 For this reason there will be no cracking of the fuel in the chamber, or distillation leaving a residue on the walls thereof. The cooling also has another effect. Air in the auxiliary chamber increases in temperature proportionate to the increase of pressure in the cylinder of the engine. Due to the contracted area of the ducts 14, there will be a lag of pressure in the auxiliary chamber behind that in the cylinder of the engine. 40 However, the increase of pressure and temperature of the air in the auxiliary chamber will be proportionate to that in the main cylinder. There will be no ignition of the fuel charge in the auxiliary chamber until 45 the air has been compressed to the point of ignition of the fuel. Due to the fact that the chamber is kept cool, there is substantially no variation of the time at which ignition will occur relative to the compression in the cylinder of the engine. For this reason, fuel 50 may be injected into the auxiliary chamber at any time after the first stroke begins, and the ignition takes place under more ideal conditions, if the fuel is injected before the

end of the compression stroke. The time at which the event of ignition occurs is solely dependent upon the area of the ducts 14, the compression in cylinder 4, and the nature of the fuel. Due to the relatively large size of the upper or outer end of chamber 12, some inert gases will remain therein. This forms an accumulator zone, so that upon explosion of the charge in the auxiliary chamber, there is a compression of the inert gases and an accumulation of energy therein. After the explosion, there is a gradual expansion of the gases in the accumulator zone forcing some of the remaining fuel charge outwardly through the ducts over an appreciable period of the power stroke, thereby approaching more nearly the ideal Diesel engine cycle. It will also be noted that fuel is sprayed transversely of the travel of the piston and into the clearance space. If fuel is sprayed directly upon the engine piston or 80 walls, it will have a tendency to be condensed with the result of forming carbonaceous deposits.

What I claim is:

1. In combination with the water jacketed cylinder of an internal combustion engine having two aligned concentric openings extending through the outer and inner walls of the cylinder head adjacent the cylinder wall, an injection nozzle comprising a conical chamber communicating through restricted openings with said cylinder, fuel being injected into said chamber before the end of the compression stroke and then mixed with air from the cylinder forced through said openings during the compression stroke whereby a primary explosion occurs which forces the fuel charge into the cylinder, said injection nozzle being formed with a cylindrical body which is mounted in the openings in said head, the reduced inner or discharge end of said nozzle being disposed to enter the cylinder at its side, a plug closing the top of said chamber, and a fuel nozzle extending through said plug into said chamber.

2. The combination as specified in claim 1 characterized by the cylindrical body of the injection nozzle having the material around the reduced inner or discharge end of the chamber removed up to the height of the inner end of the fuel nozzle so as to increase the cooling effect.

In witness that I claim the foregoing I have hereunto subscribed my name this 1st day of June, 1920.

JOHN H. SUTER.
